MARGIN CONTROL FOR DUPLICATING MACHINES

Alfred Marchev, La Grange, Ill., assignor to Ditto, Incorporated, Chicago, Ill., a corporation of West Virginia

Application March 6, 1936, Serial No. 67,468

11 Claims. (Cl. 101—132)

This invention relates to duplicating machines of the general type shown in the application of John W. Hernlund, Serial Number 44,911, filed October 14, 1935 for Duplicating machines.

5 Machines of this type employ master sheets which are mounted upon a drum and copy sheets are moistened with a suitable solvent for the ink or carbon on the master sheet immediately before they are brought into contact with the 10 side of the master sheet upon which the ink or carbon is placed.

The master sheets have the data to be duplicated formed thereon in reverse so that when a portion of the ink is dissolved off and transferred to the moistened surface of the copy sheet, it will appear in correct readable form. In practice, some readily volatile solvent such as alcohol is employed.

The present invention is embodied in a machine of the type described above which machine comprises a rotary drum having means for clamping master sheets thereto.

The machine also comprises suitable means for advancing copy sheets to the drum which means 25 may desirably constitute a pair of feed rollers. One of the feed rollers may cooperate with a moistening device so that this feed roller will supply the volatile solvent to one surface of a copy sheet as it is fed to the drum. A platen 30 roller is employed to press the copy sheets against a master sheet secured on the drum.

In machines of this character, it is necessary to change the master sheets and the improved machine embodying the present invention comprises mechanism whereby a master sheet clamped to the drum may be rapidly removed and a new master sheet may be substituted in its place.

In using a machine of this character, it is desirable oftentimes to vary the margin left at the front or head end of the copy sheet. In the aforementioned application means are provided whereby in the original setting of the drum with respect to the feed rollers, a definite margin adjustment may be made. This adjustment however, is not adequate to take care of situations wherein certain copies may need to have a wider or narrower margin than other copies may from the same master.

50 The improved machine embodying the present invention comprises mechanism whereby the margin for any copy sheet may be quickly adjusted within a substantial range by the operator.

Other features and advantages of the invention 55 will become apparent as the following description

progresses reference being had to the accompanying drawings wherein—

Fig. 1 is a plan view of a duplicating machine which embodies the invention;

Fig. 2 is a vertical sectional view taken on the line 2—2 of Fig. 1;

Fig. 3 is an enlarged fragmentary sectional view taken on the line 3—3 of Fig. 1;

Fig. 4 is a fragmentary sectional view taken on the line 4—4 of Fig. 3;

Figs. 5 and 6 are fragmentary sectional views through a portion of the drum and the feeding and platen rollers illustrating the range of margin adjustment provided;

Fig. 7 is a sectional view similar to Fig. 3 illustrating a modified form of the invention;

Fig. 8 is a fragmentary plan view of the form of the invention shown in Fig. 7;

Fig. 9 is a sectional view taken on the line 9—9 of Fig. 7;

Fig. 10 is a sectional view similar to Fig. 3 illustrating a further modification of the invention;

Fig. 11 is a sectional view taken substantially on the line 11—11 of Fig. 10;

Fig. 12 is a sectional view taken on the line 12—12 of Fig. 10;

Fig. 13 is a sectional view taken on the line 13—13 of Fig. 12;

Fig. 14 is a fragmentary sectional view taken on the line 2—2 of Fig. 1 and showing the mechanism in a changed position from that shown in Fig. 2; and

Fig. 15 is a fragmentary side elevation with certain parts broken away to illustrate the drive connection whereby the duplicating machine is operated from a rotatable hand lever.

Referring now to the drawings in which a preferred embodiment of the invention is shown, the reference characters 16 and 17 designate a pair of side frames adapted to rest upon any suitable support. The side frames 16 and 17 are secured together by any suitable means such as that shown in the aforementioned application. A drum 18 is rotatably journaled in the side frames 16 and 17 by a suitable shaft 19.

As best shown in Fig. 15, the drum 18 is adapted to be rotated by means of a hand lever 20. The hand lever 20 is keyed to a stub shaft 21 rotatably mounted in the side frame 17. The stub shaft 21 also carries a pinion 22 which meshes with a gear 23 that is keyed to the shaft 19 by key 24. The pinion 22 and the gear 23 are enclosed by a housing 25 which is secured on the outside of the side frame 17 by means of a pair of screws 26 and 27.

55

The drum 18 has a large gear 28 secured to the end thereof adjacent to the side frame 17 and this gear 28 meshes with an intermediate gear 29 that in turn drives a suitable gear not shown for rotat-
 5 ing a combined feeding and moistening roller 30. A felt covered roller 31 cooperates with the roller 30 to advance copy sheets to the drum 18 and a platen roller 32 is adapted to press copy sheets against a master sheet on the drum 18. A
 10 moistening receptacle 33 is supported in front of the moistening roller 30 and is adapted to supply a solvent liquid to the surface of the roller 30 through a felt wick 34. A copy sheet table 35 is supported on the side frames 16 and 17 and projects beneath the moistening receptacle 33 terminating adjacent to the junction or meeting lines of the rollers 30 and 31.

As described more fully in the aforementioned application, the drum 18 is provided with a plurality of grippers 36 which are adapted to project through suitable openings 37 provided in the surface of the drum 18 and clamp one edge of a master sheet 38 in a groove 39 which runs longitudinally of the drum 18. The grippers 36 are mounted upon a gripper shaft 40 which is journaled in the ends of the drum 18.

The shaft 40 has a lever arm 41 fixed thereto. This lever arm at its free end is secured to one end of a spring 42 which has its other end fixed to the 30 end of the drum and which is under tension so as to yieldingly hold the lever arm 41 in position to cause the grippers 36 to clamp a master sheet in the groove 39.

For the purpose of opening the grippers 36 a 35 hand lever 43 is mounted for rotation on the shaft 19. This hand lever has a pair of rollers 44 and 45 mounted thereon in diametrically opposite positions with respect to the shaft 19.

On the adjacent side frame 17, a pair of cam 40 levers 46 and 47 are secured. These cam levers are rotatably mounted upon a pair of stub shafts 48 and 49 and are urged toward the rollers 44 and 45 respectively by a pair of coiled springs 50 and 51 wound around the hubs of the cam levers 46 and 47 and secured at one end to the cam levers and at the other end to the side frames 17 so as to yieldingly press the cam levers toward their respective rollers 44 and 45. The lever arm 41 has a roller 52 thereon which roller is adapted to 50 ride upon the outer surfaces of the cam levers 46 and 47 as the drum is rotated.

Referring now to Fig. 14 in connection with Fig. 2, it will be noted that the position of the hand lever 43 has been changed in Fig. 14 so as to move the rollers 44 and 45 outwardly along the cam levers 46 and 47 so as to separate the cam levers. The roller 45, however, drops into a recess 53 in the cam lever 47 and the roller 44 rides upon a portion 54 of the cam lever 46 that does not effect any substantial outward movement of the cam lever 46. The roller 52 on the lever arm 41 therefore, does not contact either of the cam levers 46 or 47 when the hand lever is in the position shown in Fig. 14 and so the grippers 36 65 remain closed.

Now, however, if the hand lever 43 is moved further in a counterclockwise direction from the position shown in Fig. 14, its rollers 44 and 45 push the cam levers 46 and 47 outwardly so that either one of them will engage the roller 52 on the lever arm 41 and cause the grippers 36 to be opened. The grippers may, of course, then be closed again by returning the hand lever 43 to the position shown in Fig. 14 or the position shown in 75 Fig. 2.

The hand lever 43 also controls through a suitable mechanism which will now be described the stopping of the drum in position to receive a fresh master sheet. A master sheet tray 55 is pivotally supported between the side frames 16 and 17 by means of a pair of pins 56 and 57. A spring 58 secured at one end to a pin 59 on the master sheet tray 55 and at the other end to a pin 60 on the side frame 17 yieldingly presses the master sheet tray 55 toward the surface of the drum 18. The master sheet tray has a stop projection 61 thereon which projection normally engages a pin 62 to prevent the master sheet tray from being lowered into the drum surface.

The pin 62 is secured to a block 63. The block 63 is pivoted on a stub shaft 64 mounted in the side frame 17 and carries an adjustable stop member 65 which is adapted to engage a tie rod 66 and limit the movement of the block 63 in clockwise direction about the shaft 64. A spring 67 secured at one end to a pin 68 on the side frame 17 and at the other end to a pin 69 on the block 63 is adapted to urge the block 63 into its limiting position shown in Fig. 14 where the stop member 65 engages the tie rod 66.

Integral with the block 63, there is an arm 70 which arm is connected by a link 71 to a projection 72 on the hub of the hand lever 43. Thus, when the hand lever 43 is moved to the position shown in Fig. 2, the link 71 pulls the arm 70 in a counterclockwise direction to hold the block 63 in the position shown in Fig. 2. In this position of the block 63, the pin 62 engages the portion 30 35 of the master sheet tray 55 and holds the master sheet tray away from the drum surface.

It will be noted that the link 71 is slotted as indicated at 73. When the hand lever 43 is moved to the position shown in Fig. 14, the link 71 is moved to permit clockwise movement of the arm 70 and the block 63 by virtue of reflex action of 40 spring 67. This clockwise movement is stopped when the stop member 65 engages the tie rod 66. The slots 73 in the link 71 however, permits further movement of this link and therefore further movement of the hand lever 43 to open the 45 grippers 36.

The block 63 also has integral therewith a stop arm 74. This stop arm is positioned by the movement of the arm 70 and block 63 just described in the path of a stop pin 75 that is mounted on 50 a cam member 76 fixed to the end of the drum 18. Thus, a positive stop is provided for the drum when the hand lever 43 is moved into the position shown in Fig. 14.

To prevent reverse movement of the drum and 55 to latch it in a definite position, there is a latch lever 77 pivoted on the stub shaft 64 and yieldingly held against the pin 62 by a spring 78. The latch lever 77 as illustrated in Fig. 14 is adapted to drop behind the stop pin 75 where it extends 60 on the opposite side of the cam member 76 from the portion of the stop pin 75 engaged by the arm 74.

The manner in which the drum 18 is stopped after each printing operation in position to have 65 a new copy sheet applied to a master-sheet thereon will now be described.

Referring now particularly to Fig. 3 in connection with Fig. 1, it will be noted that at the end of the drum adjacent the side frame 16, a cam plate 80 is fixed to the drum by means of suitable studs 81 and 82. The plate 80 is apertured for the shaft 19. This cam plate in rotat- 70 ing with the drum is adapted to engage a roller 83 which is mounted on the end of an arm 84. 75

The roller 83 rides up upon an advancing surface 85 on the cam plate 80 and drops into a recess 86 in the cam plate to effect stopping of the drum in the desired position to receive a new copy sheet.

Referring now to Figs. 5 and 6, if it is desired to have a copy sheet registered accurately with the forward edge of a master sheet then the stop position of the drum must be such that the distance from the forward edge of the master sheet along the drum surface to the point which the platen roller 32 engages the drum must be substantially equal to the distance which the rollers 30 and 31 will advance a copy sheet 87 while the drum is moving to bring the front edge of the master sheet to the platen roller. The speed of rotation of the roller 30 is preferably so made as described in the aforesaid application as to cause the advance of a copy sheet at a rate almost the same as the surface speed of the drum. Preferably, the rollers 30 and 31 advance a copy sheet a little slower than the surface speed of the drum.

Now, however, in the event that a greater or less margin is wanted on the copy sheet than is present on the master sheet attached to the drum, there must be some change in the relative position of the master sheet grippers and the platen roller 32 at the time the drum stops with the cam plate 80 and the roller 83 for stopping rotation of the drum in copy sheet feeding position. This adjustment of margins on copy sheets is accomplished by mounting the arm 84 which carries the roller 83 so that it can be moved circumferentially of the drum.

In order to accomplish this result, a hand lever 88 is pivoted to the side frame 16 by means of a pin 89. The arm 84 is then pivoted to the hand lever 88 by means of a pin 90. The arm 84 has a portion 91 which extends over behind the hand lever 88 as shown most clearly in Fig. 1. Also a spring 92 is coiled around the pin 90 and hooked over the arm 84 at one end and the hand lever 88 at its other end so as to press the roller 83 against the cam plate 80. The portion 91 of the arm 84 acts as a stop to limit the counterclockwise movement of the cam 84 by engaging with the hand lever 88.

The hand lever 88 projects up above the side frame 16 and is provided with a bracket 93 in which a pin 94 is mounted. The side frame 16 has a top flange 95 which is provided with a plurality of apertures 96 adapted to receive a reduced end portion 97 of the pin 94. A spring 98 is mounted on the pin 94 within the bracket 93 and engages a flange 99 on the pin 94 so as to yieldingly press it toward the flange 95 of the side frame 16. The apertures 96 thus cooperate with the pin 94 to lock the hand lever 88 in any one of the several positions indicated by the apertures 96.

By moving the hand lever 88 from one position to another, the stop position of the drum 18 may be shifted over a substantial range. Some evidence of the range is indicated by observing the position of the grippers in Fig. 5 and comparing this with the position of the grippers in Fig. 6.

Thus in Fig. 5, the copy sheet 87 if started into rollers 30 and 31 at the time the rollers started rotating, would reach the junction of the drum 18 and the platen roller 32 considerably in advance of the master sheet 38. This would provide a greater margin on the copy sheet 87 than that provided on the master sheet 38.

In Fig. 6, the result of advancing the stop position of the drum is shown. If the drum were

started to rotate with a copy sheet in position and the parts in the positions shown in Fig. 6 then the forward edge of the master sheet would pass the platen roller 32 before the copy sheet reached the junction of the drum 18 and the platen roller 32. In this case the copy sheet margin would be considerably less than that provided on the master sheet.

Referring now to Figs. 7 to 9 inclusive, these figures disclose a modified form of margin adjustment which cooperates with the cam plate 80 and its cam surfaces 85 and 86. The margin adjustment in this case is one which can be made much more accurately and in finer divisions than with the mechanism shown in Figs. 3 to 6 inclusive. This form of the invention utilizes the roller 83 and the spring pressed arm 84. The spring pressed arm 84 however is pivoted upon a pin 100 which is formed on a sliding block 101.

The sliding block 101 is mounted on the side frame 16 by means of a pair of guides 102 and 103 fixed to a thickened portion 104 on the side frame 16 by suitable screws. The block 101 is grooved and the guides 102 and 103 have tongues fitting in the grooves of the block 101. A spring 105 is wound around the pin 100 and has one end hooked over the arm 84 while its other end is hooked over a pin 106 also mounted on the block 101. To limit the distance to which the spring 105 can turn the arm 84, the arm 84 is provided with a stop projection 107 which is adapted to engage the pin 106. The block 101 carries a pointer 108 which is secured to the block by a screw 109 and which fits over the pin 100. This pointer 108 projects over the top flange of the side frame 16 and has a pointed end 110 adapted to cooperate with suitable graduations shown at 111 in Fig. 8.

For moving the block 101 so as to shift the position of the arm 84, this block is screw threaded 40 to receive a screw threaded adjusting rod 112. This rod is rotatably secured in a lug 113 formed in the side frame 16 by means of a pair of collars 114 and 115 and the end of the rod is provided with a slot at 116 to receive a screw driver or other suitable tool for turning the rod. It will be understood, of course, that by rotation of the rod 112, the block 101 may be moved lengthwise in its guide 102 and 103 to thereby change the stop position of the drum. This method of adjustment enables the setting of the margin with a high degree of accuracy.

Referring now to Figs. 10 to 13 inclusive, a further modification is shown of the means for stopping the drum in position to receive a new copy sheet. In this form of the invention, the cam plate 80 remains the same and its cam surfaces 85 and 86 are not changed.

The side frame 16 has a boss 117 thereon which has a pivot pin 118 screw threaded into it. The pivot pin supports a lever 119 which lever projects up along the side frame 16 and fits in a recess 120 provided in the top flange of the side frame 16. The top flange is made thicker adjacent the recess 120 and has mounted therein a pair of spaced spring pressed detents 121 and 122. The lever 119 is adapted to be moved by hand over these detents so that it may be held in place in three positions: one position where it is shown in Fig. 10, a second position where it is between the two detents 121 and 122, and a third position where it is between the detent 121 and the adjacent end of the recess 120.

The lever 119 carries a roller 123 to engage the cam surfaces 85 and 86. The lever 119 has a

U-shaped bracket 124 thereon. This bracket has the legs thereof slotted with a plurality of slots 125, 126, 127 and 128.

In the slots just described are bearing blocks 129 and 130. The bearing block 129 extends into the slots 125 and 126 and is widened between these slots so as to hold it in place. Similarly, the block 130 is guided in the slots 127 and 128. These blocks are pressed downwardly by a pair of springs 131 and 132 against a shaft 133 that extends lengthwise through the U-shaped bracket 124. This shaft has a head 134 at one end and a pin 135 at the other end to prevent its moving endwise in the bracket.

The downward movement of the shaft 133 is limited by a pair of pins 136 and 137. The roller 123 is carried by the shaft 133. It will be evident from the above description that the roller 123 can move up and down so as to ride over the cam surfaces 85 and 86. It will also be obvious that the springs 131 and 132 will yieldingly press the roller against the cam surfaces.

While certain embodiments of the invention have been shown and described, it is to be understood that it is capable of many modifications. Changes, therefore, in the construction and arrangement may be made without departing from the spirit and scope of the invention as disclosed in the appended claims in which it is the intention to claim all novelty inherent in the invention as broadly as possible in view of the prior art.

Having thus described the invention what I claim as new and desire to secure by Letters Patent is:

1. In a duplicating machine of the character described, a framework, a drum rotatably journaled therein and having means thereon to clamp a master sheet thereto, feeding rollers adjacent to said drum, means interconnecting said drum and said rollers whereby to cause rotation of the rollers when the drum is rotated, an adjustable stop means for said drum, said stop means comprising a cam fixed to said drum and having a stop recess therein, a roller carried by said framework and adapted to engage said cam to stop the drum, and manually operable means for shifting said roller on the frame to vary the stop position of the drum.

2. In a duplicating machine of the character described, a framework, a drum rotatably journaled therein and having means thereon to clamp a master sheet thereto, feeding rollers adjacent to said drum, means interconnecting said drum and said rollers whereby to cause rotation of the rollers when the drum is rotated, an adjustable stop means for said drum, said stop means comprising a cam fixed to said drum and having a stop recess therein, a roller carried by said framework and adapted to engage said cam to stop the drum, and manually operable means for shifting said roller on the frame to vary the stop position of the drum, said manually operable means comprising a spring pressed arm on which said cam roller is mounted, and a lever pivoted on the framework and carrying said arm, said lever being pivoted on an axis parallel to the drum axis and being movable to shift said cam roller in the direction of movement of the periphery of said drum.

3. In a duplicating machine of the character described, a framework, a drum rotatably journaled therein and having means thereon to clamp a master sheet thereto, feeding rollers adjacent to said drum, means interconnecting said

drum and said rollers whereby to cause rotation of the rollers when the drum is rotated, an adjustable stop means for said drum, said stop means comprising a cam fixed to said drum and having a stop recess therein, a roller carried by said framework and adapted to engage said cam to stop the drum, and manually operable means for shifting said roller on the frame to vary the stop position of the drum, said manually operable means comprising a spring pressed arm on which said cam roller is mounted, and a lever pivoted on the framework and carrying said arm, said lever being pivoted on an axis parallel to the drum axis and being movable to shift said cam roller in the direction of movement of the periphery of said drum, said lever and said framework having cooperating portions for holding the lever in any one of a plurality of positions.

4. In a duplicating machine of the character described, a framework, a drum rotatably journaled therein and having means thereon to clamp a master sheet thereto, feeding rollers adjacent to said drum, means interconnecting said drum and said rollers whereby to cause rotation of the rollers when the drum is rotated, an adjustable stop means for said drum, said stop means comprising a cam fixed to said drum and having a stop recess therein, a roller carried by said framework and adapted to engage said cam to stop the drum, and manually operable means for shifting said roller on the frame to vary the stop position of the drum, said manually operable means comprising a spring pressed arm carrying said cam roller, a block movably mounted on the framework and supporting said arm, and means for shifting said block on the framework in the direction of movement of the periphery of said drum.

5. In a duplicating machine of the character described, a framework, a drum rotatably journaled therein and having means thereon to clamp a master sheet thereto, feeding rollers adjacent to said drum, means interconnecting said drum and said rollers whereby to cause rotation of the rollers when the drum is rotated, an adjustable stop means for said drum, said stop means comprising a cam fixed to said drum and having a stop recess therein, a roller carried by said framework and adapted to engage said cam to stop the drum, and manually operable means for shifting said roller on the frame to vary the stop position of the drum, said manually operable means comprising a spring pressed arm on which said cam roller is mounted, and a lever pivoted on the framework and carrying said arm, said lever being pivoted on an axis parallel to the drum axis and being movable to shift said cam roller in the direction of movement of the periphery of said drum, a spring pressed pin on said lever, and said framework having spaced sockets for said pin whereby to position said lever in any one of several positions.

6. In a duplicating machine of the character described, a framework, a drum rotatably journaled therein and having means thereon to clamp a master sheet thereto, feeding rollers adjacent to said drum, means interconnecting said drum and said rollers whereby to cause rotation of the rollers when the drum is rotated, an adjustable stop means for said drum, said stop means comprising a cam fixed to said drum and having a stop recess therein, a roller carried by said framework and adapted to engage said cam to stop the drum, and manually operable means for shifting said roller on the frame to vary

the stop position of the drum, said manually operable means comprising a lever on said framework and carrying said roller, and spring means thereon for pressing the roller toward the cam.

7. In a duplicating machine of the character described, a framework, a drum rotatably journaled therein and having means thereon to clamp a master sheet thereto, feeding rollers adjacent to said drum, means interconnecting said drum and said rollers whereby to cause rotation of the rollers when the drum is rotated, an adjustable stop means for said drum, said stop means comprising a cam fixed to said drum and having a stop recess therein, a roller carried by said framework and adapted to engage said cam to stop the drum, and manually operable means for shifting said roller on the frame to vary the stop position of the drum, said manually operable means comprising a lever on said framework and carrying said roller, and spring means thereon for pressing the roller toward the cam, and means on the framework for releasably holding said lever in either one of a plurality of positions.

8. In a duplicating machine of the character described, a framework, a drum rotatably journaled therein and having means thereon to clamp a master sheet thereto, feeding rollers adjacent to said drum, means interconnecting said drum and said rollers whereby to cause rotation of the rollers when the drum is rotated, and adjustable stop means for said drum, said stop means comprising a cam fixed to said drum and having a stop recess therein, a roller carried by said framework and adapted to engage said cam to stop the drum, and manually operable means for shifting said roller on the frame to vary the stop position of the drum, said manually operable means comprising a lever on said framework and carrying said roller, and spring means thereon for pressing the roller toward the cam, and means on the framework for releasably holding said lever in either one of a plurality of positions, said last named means comprising spring pressed detents on the framework in the path of the lever.

45 9. In a duplicating machine of the character described, a framework, a drum rotatably journaled therein and having means thereon to

clamp a master sheet thereto, feeding rollers adjacent to said drum, means interconnecting said drum and said rollers whereby to cause rotation of the rollers when the drum is rotated, an adjustable stop means for said drum, said stop means comprising a cam fixed to said drum and having a stop recess therein, a roller carried by said framework and adapted to engage said cam to stop the drum, and manually operable means for shifting said roller on the frame to vary the stop position of the drum, said manually operable means comprising a spring pressed arm carrying said cam roller, a block movably mounted on the framework and supporting said arm, a screw rotatable in said block, and a member fixed on the framework in which screw is threaded.

10 10. In a duplicating machine of the character described, a framework, a drum rotatably journaled therein, and adjustable stop means for said drum, said stop means comprising a member rotatable with the drum and having a stop thereon, a second member carried by the framework and movable into the path of said stop to limit advance movement of the drum, and manually operable means for shifting said second member on the frame to vary the stop position of said drum, said manually operable means comprising a support for said second member movably mounted on the framework and a screw for shifting said support on the framework.

15 11. In a duplicating machine of the character described, a framework, a drum rotatably journaled therein, and adjustable stop means for said drum, said stop means comprising a member rotatable with the drum and having a stop thereon, a second member carried by the framework and movable into the path of said stop to limit advance movement of the drum, and manually operable means for shifting said second member on the frame to vary the stop position of said drum, said manually operable means comprising a spring pressed arm on which said second member is mounted, a support for said arm movably mounted on said framework and means on the framework for releasably holding said support in any one of a plurality of positions.

ALFRED MARCHEV.
